DISPLAY CABINET

George F. Reed, Pittsburgh, Pa.

Application September 22, 1933, Serial No. 690,593

16 Claims. (Cl. 40—32)

This invention relates to improvements in display cabinets of the type including a display card formed of transparent material mounted upon an endless conveyor and adapted to be illuminated during its passage in back of a window or display opening.

Particularly, this invention relates to improvements upon advertising and display devices as shown in the patent of George F. Reed, No. 1,872,607, issued August 16, 1932.

The primary object of this invention is to provide an endless display sign having floating sections hinged together and secured along the marginal edges to an endless carrier chain.

A further object of this invention is to provide a resilient connection between the carrier chain and the floating panels whereby breakage thereof will be minimized.

A still further object of this invention is to provide hinge bars for the transparent panel frames which are provided with novel connections adapted to be attached to the carrier chain for the purpose of guiding the panel frames in a unique manner.

A still further object of this invention is to provide fastening means between the panel carrier and the panels adapted to allow relative movement to reduce the strain upon the transparent panel and the resultant breakage.

A still further object of this invention is to provide a casing formed of cast sides, top and bottom wall members which are preferably cellular to reduce the weight and minimize the production cost.

A still further object of this invention is to provide a novel reflector mounted directly in back of the display window formed in the casing front wall which is adapted to eliminate blind spots and glare when the advertising panels are viewed from the outside of the casing.

A still further object of this invention is to provide in combination with the reflector a piece of translucent material, preferably glass, for the purpose of diffusing the light before it is projected onto the transparent display panel thereby giving an even distribution of light whereby the panels may be more clearly visible.

A still further object of this invention is to provide a floating support for the drive motor and reduction gearing which greatly reduces the vibration and adds to the quiet operation of the device.

A still further object of this invention is to provide rubber cushioned feet upon the cabinet having means for receiving a bolt or the like where-

by the display casing may be mounted on the trunk carrier of a motor vehicle if desired.

Other objects and advantages of the invention will become apparent during the course of the following description, forming a part of the specification, taken with the drawings, wherein,

Figure 1 is a perspective view of the casing illustrating the silvered front wall having an un-silvered portion for the projection of the display panels;

Figure 2 is a rear elevational view of a motor vehicle showing the display cabinet secured to the trunk rack thereof;

Figure 3 is an enlarged fragmentary view in section illustrating one of the supporting feet provided with a cushion device and a fastening screw for the purpose of attaching the casing to the adaptation of the invention shown in Figure 2;

Figure 4 is a front elevational view of the device embodying this invention illustrating the front wall removed for the purpose of showing the manner and arrangement of the endless carriers relative to the transparent display panels and panel carriers;

Figure 5 is a side elevational view of one of the side frame members illustrating the bearings for supporting the endless carrier sprockets and shafts;

Figure 6 is a vertical cross-sectional view of one of the side pre-cast display members and further illustrating the journal bearings for the endless carrier shafts and sprocket wheels;

Figure 7 is a top elevational view of a pre-cast bottom frame member which is preferably cellular for the purpose of reducing weight and production costs;

Figure 8 is a transverse cross-sectional view of the same showing the centrifugal flanges for receiving fastening elements adapted to secure the side frame members in place;

Figure 9 is a perspective view of a casting particularly adapted for supporting the reflector behind the window and also for supporting the opaque transparent material mounted in front of the reflector and adapted to diffuse the light rays projected therethrough;

Figure 10 is a vertical cross-sectional view of the display device illustrating the drive arrangement and the manner in which the endless carriers are arranged relative to the casing and light reflector;

Figure 11 is a fragmentary enlarged view of one of the display panels illustrating the manner in which the same is carried by the endless carrier

and further showing the connection between the panel carriers and endless chain carriers;

5 Figure 12 is an enlarged fragmentary view partly in cross-section, illustrating one of the pintle rods provided for connecting adjoining panel carriers and showing the manner in which the rods are attached to the sprocket chains by means of the removable pins;

10 Figure 13 is an enlarged fragmentary view illustrating in detail the connection between the panel carrier frames and the endless carrier chains whereby the panel carrier frames will be 15 floatingly mounted relative to the endless carriers;

15 Figure 14 is an enlarged fragmentary cross-sectional view taken on lines 14—14 of Figure 13, looking in the direction of the arrows, illustrating the resilient connection between the panel frames and the endless carriers;

20 Figure 15 is an enlarged cross-sectional view taken on line 15—15 of Figure 11 looking in the direction of the arrows illustrating the floating connection between the resilient clips and the panel frame whereby a limited movement may be 25 provided to reduce tearing and breakage of the transparent panels;

25 Figure 16 is an enlarged fragmentary cross-sectional view taken on line 16—16 of Figure 11, looking in the direction of the arrows illustrating the 30 loosely mounted rivets for connecting the transparent panels to the panel frame along the side margins thereof;

35 Figure 17 is an enlarged fragmentary front elevational view of one of the resilient connections between the panel supporting frame and the endless carrier chain showing the manner in which the former may be distorted without bending or twisting the chain or tearing or breaking the panel frame carrier;

40 Figure 18 is an enlarged fragmentary cross-sectional view illustrating the resilient panel clip and the manner in which the same is secured to the endless carrier chain; and

45 Figure 19 is a vertical cross-sectional view taken on line 19—19 of Figure 11, looking in the direction of the arrows illustrating the hinge connection between the panel frame and illustrating in detail the manner in which the transparent panels are loosely held between the leaves of the hinge so that the free ends of the display panel 50 will have a loose connection therewith.

55 In the drawings, wherein for the purpose of illustrating the invention and wherein like reference characters will be employed to designate like parts throughout the same, the reference character 5 will generally be employed to designate a casing having cellular frame side members having vertical uprights 6 connected by transverse cast bars 7, 8, 9, 10 and 11. The cellular side frame members are connected at the top and bottom by cellular casting 12 as shown in Figure 7 having transverse cast bars 13 and 14 arranged in criss-cross fashion. The side frame members may be connected to the top and bottom members by suitable nuts and bolts so that the cast feet 15 60 will project beyond the bottom member as clearly shown in Figures 1, 3, 4 and 10.

65 After the side, top and bottom frame members have been assembled by means of fastening devices the sheet metal side plates 16 may be secured thereto and held in place by vertical angle irons 17 as by means of nuts and bolts 18 and a cover 19 may be fitted upon the frame work so that the side flanges 20 overlap the side walls 16 and vertical angle irons 17. Fastening members 70

such as screws 21 may be provided for holding the cover in place.

5 Similarly, a bottom angle iron 22 may be provided having a bottom flange which may be connected to the vertical angle irons 17 for the purpose of finishing the structure and producing a completed cabinet. The front wall 23 is preferably formed of a piece of silvered glass presenting a mirror effect having a portion thereof as at 24 unsilvered adapted to form a window behind 10 which the display panels may be moved and illuminated for display purposes. Certain sections or portions of the silvered panel 23 may be colored as at 25 to produce a modernistic effect and add to the attractiveness of the display sign. 15

The rear wall 26 is movably held in place at the top and bottom by means of being received between the flange 20 of the cover 19 and the flange 27 of the top and bottom frame members 12. It will be noted that the angle irons 22 extending 20 around the bottom edge of the casing forms a seat for the lower portion of the rear wall 26 and by lifting upwardly upon the rear wall 26 by means of a hand hold 28, the lower edge of the removable rear wall 26 may be freed from between the flange of the angle bar 22 and the flange 27 formed on the lower frame piece 12. Louvers 29 may be provided in the rear wall for the purpose of ventilation and allowing the escape of heat produced by the electric motor and 30 illuminating means.

35 The front wall 23 may be formed of glass and has its edges received in a similar fashion as the rear wall such as between the marginal flange 27 of the top and bottom members and angle iron 22. If desired, a packing strip 30 may be interposed between the flange 20 of the top wall 19 and the angle bar 22 so that shocks received by the casing will not fracture or break the glass front panel 23. 40

45 Each of the supporting feet 15 may be provided with rubber cushions 31 held in place by friction and should it be desired to connect the supporting feet 15 to a rigid support such as the trunk rack 32 of a motor vehicle 34 shown in Figure 2 each supporting foot 15 may be provided with a screw threaded bore 33 for receiving a fastening bolt 35. The cabinet or casing may be fastened securely to other forms of supports such as tables or the like by employing the same fastening means extending into the screw threaded openings 33 formed in each of the supporting feet. 50

55 Journalled at opposite ends of the transverse member 3 formed in the side frame member 6 in bearings 40 are rotary shafts 41 provided with sprocket wheels 42 rigidly secured thereto. The sprocket wheels 42 are arranged on opposite ends of the shafts 41 so that there will be provided a set of sprocket wheels 42 in the front portion of the casing and a set of sprocket wheels in the rear portion of the casing adjacent the upper end thereof. 60

65 Journalled in bearings 43 and 44 formed on one of the lower cross bars 10 of the pre-cast side frame member 6 are rotary shafts 45 and 46 respectively. The bearing 44 is provided with an eccentric 47 for the purpose of adjusting the rotary shaft 46 to increase or decrease the tension on the sprocket chain which will be hereinafter more fully described. In order to hold the eccentric 47 in an adjusted position, a set screw 48 is provided for this purpose. 70

75 Secured to opposite ends of the shafts 45 are sprocket wheels 49 while similarly arranged 75

sprocket wheels 50 are secured rigidly to opposite ends of the shaft 46.

Also journalled in bearings 51 formed in the side frame members 6 on the transverse bars 9 is a shaft 52 having rigidly secured to opposite ends thereof sprocket wheels 53. In addition, the shaft 52 is provided with a sprocket wheel 54 held in place in a rigid manner, adapted to receive power from a suitable motor.

Passing over the sprocket wheels 42, 49, 50, and 53 is a pair of endless chains 55 after the fashion shown in Figure 10 and said sprocket chains 55 may be rotated by means of the sprocket wheel 54 upon the shaft 52 which is connected to a sprocket wheel 56 secured on a shaft 57 which extends out of a reduction gearing box 58 by means of an endless sprocket 59. An electric motor 60 may have its armature shaft 61 connected to the drive shaft 62 of the reduction gearing 58 by means of a couple 63 and said electric motor 60 and reduction gearing 58 may be carried by a floating motor support 64 resiliently carried by the side frame members 66 by means of brackets 65 having inwardly extending arms 66 so that one end 67 of a coil spring 68 is connected thereto and the opposite end of the coil spring 69 is connected to the plate or motor support 64. In this manner, rotary motion is imparted to the rotary shaft 52 in a silent and even manner which causes the sprocket chain 55 to travel over the sprocket wheels 42, 49, 50 and 53 in a slow and even travelling motion.

The position and arrangement of the sprocket wheels and sprocket chains is very similar to the form of the invention shown in the George F. Reed Patent No. 1,872,607 issued August 16, 1932.

An important feature of the invention resides in the manner of arranging the display panels 70 which are preferably formed of a flexible transparent material and which may have printed or otherwise secured thereon designs or advertising matter. It is intended to have a plurality of transparent display panels 70 having longitudinal marginal strips 71 formed of a springy material preferably Swedish steel and rivets 72 may extend through the marginal strips 71 and marginal edges of the display panels and said rivets may be arranged in a staggered manner and may further be formed smaller than the openings in the lower edge of the display panels 70 and the marginal strips 71, so that lateral play may be produced between the parts. The end portions of the transparent display sheets 70 are preferably cut on a bias as at 73 to form flap-like end portions adapted to be received between hinge leaves 74 which are U-shaped in cross-section and are provided with enlarged pintle receiving loops 75. Rivets 76 may connect the hinge leaves 74 with the marginal strips 71.

Extending through the pintle receiving loops 75 of the hinge members is a rod 77 having an axial bore 78 formed in the opposite ends thereof and each of the bores 78 is adapted to receive the reduced portion of a pin 79 formed on the end of one of the sprocket chain axles 80 as clearly shown in Figure 12 and interposed between the reduced portion 79 and the axle 80 is an annular boss 81 adapted to engage the inner edge of the sprocket chain links 55 and simultaneously the outer end of the pintle rod 77. It is obvious, that by separating the sprocket chains 55, that is moving the same away from each other, that the pintle rods 77 may be withdrawn from the reduced pins 79 for the purpose of removing the panels

70 and their enclosing frames 71. It is to be understood that the free ends of the panels 70 are slipped in between the hinge leaves 74 and are not fastened but are allowed to move relative thereto. The connection constitutes a means of guiding the free ends of the transparent panels 70 rather than providing a securing means therefor.

It will be noted that the transparent panels 70 and frames 71 are secured to the endless carrier chains 55 in much the same manner as the transparent panels shown in the George F. Reed Patent No. 1,872,607 and in addition to the guide means or pintle rods 77 for connecting the transparent panels to the endless chains, there is provided side resilient clips which connect the marginal metal strips 71 to the sprocket chain 55 in a manner which will allow relative movement between the strips and chain without tearing or otherwise breaking the transparent panels 70. The resilient connection comprises at spaced intervals angle members 82 having studs 83 provided with reduced screw threaded portions 84. The studs 83 are adapted to extend through eyelets 72 which connect the marginal strips 71 with the transparent panels 70 and it will be noted, that the openings formed in the eyelets or rivets 72 are of a greater diameter than the over-all dimension of the boss or stud 83 so that a limited amount of play may be provided and whereby the transparent panels will be floatingly carried by the sprocket chain 55. Threaded on the upper screw threaded reduced portion 84 of the stud 83 is a nut 85 to secure the bracket 82 in place and said bracket 82 is provided with a portion 86 which extends in a parallel plane with the side strip 71. The free end of the parallel portion 86 extends upwardly as at 87 and is provided with spaced openings for receiving elongated axles 88 which also form pins for the connecting links of the sprocket chain 55 as clearly shown in Figures 13, 14 and 15. The free ends of the axles 88 are connected by means of a link 89 which is substantially similar to one of the side links of the sprocket chain 55 and said link is held in place by means of a chain clip 90. Interposed between the upturned end 87 of the carrier bracket 82 and the connecting link 89 are coil springs 91 which encircle the elongated axles or studs 88. This construction allows the brackets 82 to move relative to the sprocket chain 55 as shown in Figure 7 in a distorted manner which is produced when certain of said panels 70 are passing over the sprocket wheel 42, 49, 50 and 53. Figure 18 shows an elongated axle 88 having a reduced portion 88a which connects the links of the chain 55.

When certain of the transparent panels 70 pass over the sprocket wheels as above mentioned, they become distorted and the bracket 82 will pull away from the chain 55 against the action of the coil springs 91. Direct pull may be overcome by means of the coil springs 91 in addition to longitudinal stresses or strains which produce the disarrangement shown in Figure 17. Under these conditions, only one of the coil springs 91 will compress while the other will remain in its normal position.

In Figure 19 is shown in detail, one of the pintle rods 77 which is shown in cross section so that the transparent panels 70 may have the free ends secured therebetween as at 70a. It is intended to form the hinge leaves 74 with pintle receiving loops 75 arranged and spaced alternately at the top and bottom so that the entire 75

frame may be removed from the carrier chain 55 and another frame substituted carrying different advertising matter without altering the frame or the adjacent hinge leaves 74 along with 5 the pintle receiving loops 75.

Supported by the side frame members 6 and positioned directly in back of the unsilvered portion 44 of the mirror 23 is a rectangular frame member 93 clearly shown in Figure 9 in perspective. The frame member 93 is provided with oppositely directed arms 94 having openings 95 for receiving fastening elements such as screws or the like. The rectangular frame 93 is adapted to define a window so that the transparent display panels may be clearly visible from the exterior of the casing. Formed integral with the oppositely extending arms 94 of the rectangular frame 93 and extending inwardly therefrom are angle brackets 96 having offset portions 97 provided with apertures 98 whereby a mirror or reflector 99 may be secured to the offset portions 97 by means of machine screws 100 extending therethrough and passing through the openings 98. The reflector 99 is provided with longitudinal angular surfaces 101, 102, 103 and 104 for the purpose of directing the rays of light emitted from electric light bulbs 105 positioned as shown in Figure 10 between the respective angular walls 102, 103 and 101 and 104. The light emitted 20 from the bulbs 105 is projected through an opaque panel 106 where the light is diffused and illuminates one of the transparent panels 70 which will be positioned in back of the rectangular frame or window 93 as when being carried by the carrier chain 55. The opaque panel 106 may be fastened in place upon the offset portion 97 of the rectangular frame 93, being mounted between the offset portion 97 and the reflector 99 so that the screws 100 will securely clamp the 30 opaque material 106 therebetween. At opposite sides of the rectangular frame 93 there may be provided an angle strap 108 having its free ends 109 securely retained in place by the screws 100. The angle straps 108 at opposite ends of the reflector 99 may retain the electric lamp bulbs 105 in their spaced positions and at the same time 40 may form a brace for the reflector 99.

One of the side frame members 6 is provided with a cast portion 110 including a downwardly 50 extending portion 111 projecting downwardly from the journal 51 and branching into arms 112 which connect to the transverse frame bar 10 thereby forming a pocket 113 at opposite ends of which are cut outs 114. Received within the opening 113 is an electric switch 115 of a double type having a set of contacts 116 to which may be connected line wires 117 for feeding current to the electric bulbs 105. The bulbs may be connected in series as by means of a lead line 60 118. The switch casing 115 is also provided with contacts 119 having lead lines 120 which may connect to the electric motor 60. Power is supplied through the switch housing 115 by means of a cable 121 adapted to be connected to a suitable source of current capable of illuminating the bulbs 105 and operating the motor 60. The switch casing 115 partially extends through an opening 122 formed in one of the side walls 116 and said switch casing 115 is provided with operating buttons 123 whereby the motor or electric 70 bulbs may be operated selectively.

Formed in one of the side walls 16 is an opening adjacent the electric bulb 105 which is adapted to be closed by a cover plate 124 held in place 75 by suitable machine screws 125. By removing

the cover plate 124, the electric bulbs 105 may be easily reached for the purpose of repair or if desired, the reflector 99 may be wiped and cleaned as well as the opaque glass or plate 106.

It is to be understood, that various changes 5 in the shape, size and arrangement of parts may be resorted to without departing from the spirit of the invention or the scope of the sub-joined claims, and that the form herewith shown and described is to be taken as the preferred embodiment 10 of the same.

I claim:—

1. In display apparatus of the character described, a pair of endless carriers constructed and arranged to travel in a tortuous path, and display panels supported on the carriers for limited movements relative to the carriers whereby disrupting strains on the panels are eliminated when the latter travel in tortuous paths, the panel support on the carriers including a tensioned clip 20 having relatively movable parts.

2. In a display apparatus of the character described, an endless carrier movable through arcuate paths in a cycle of operation, and panels loosely carried by the carrier and adapted to move relative to the carrier when passing through arcuate paths for relieving pulling strains on the panels, the connection between the carrier and panel including a tensioned clip having relatively movable parts.

3. In display apparatus of the character described, an endless carrier constructed and arranged to travel in a tortuous path, and hinged connected display panels resiliently attached to the carrier at opposite sides thereof, each panel 30 including a frame and a panel sheet loosely supported in the frame for movement relative to the frame during travel of the carrier and frame.

4. In a display apparatus of the character described, an endless carrier movable through arcuate paths in a cycle of operation, and hinged connected display panels resiliently attached to the carrier at opposite sides thereof, each panel including a frame and a panel sheet loosely supported in the frame for movement relative to the frame during travel of the carrier and frame.

5. In a display apparatus of the character described, an endless carrier movable through arcuate paths in a cycle of operation, and hinged connected display panels resiliently attached to the carrier, each panel including a rectangular frame having a pair of strips at the hinged end and a panel sheet loosely attached to the sides of the frame and freely extending at its ends between the pairs of frame strips.

6. A display device of the character described comprising a casing, an endless carrier mounted in the casing, translucent display panels mounted on the endless carrier, resilient connections therefor and means for driving the endless carrier, the resilient connections including a two part spring clip having the parts respectively connected to the carrier and panel.

7. A display device of the character described comprising a casing, horizontal shafts mounted in the casing, sprocket wheels secured to opposite ends of said shafts, a pair of spaced sprocket chains passing over the sprocket wheels, a display sign mounted between the sprocket chains and moving in spaced relation to the shafts, and resilient connections for securing the display signs to the sprocket chains and moving them in arcuate paths centering on the shafts.

8. A display device of the character described, comprising a casing having a display opening

therein, rotary horizontal shafts mounted in the top and bottom of the casing, sprocket wheels mounted at opposite ends of the rotary shafts, a sprocket chain for each sprocket wheel at the ends of the rotary shafts, transparent display signs, spring clips connecting the display signs to the sprocket chains, illuminating means rearwardly of the display opening and the adjacent run of the display sign, and a crenelated reflector plate rearwardly of the illuminating means having angle portions projecting between the illuminating means for maximum reflection.

9. A display device of the character described comprising a casing having a display opening therein, a pair of parallel rotary shafts horizontally mounted in the top of the casing, a similar pair of shafts mounted in the bottom of the casing, sprocket wheels mounted on opposite ends of the shafts, endless sprocket chains passing over the sprocket wheels, display signs resiliently supported between the sprocket chains, the support including a series of tensioned multi-part spring clips, illuminating means rearwardly of the display opening and the adjacent run of the display sign, a crenelated reflector plate rearwardly of the illuminating means having angle portions projecting between the illuminating means for maximum reflection and means for rotating the sprocket wheels.

10. A display device comprising a casing, an endless carrier mounted therein, comprising spaced sprocket chains, display panels carried between the sprocket chains, an angle bracket loosely secured to said display panel, guide bars secured to the sprocket chain, coil springs encircling the guide bars and engaging the angle bracket, a plate secured to the free ends of the guide bars for engaging the opposite end of the coil spring whereby movement between the display panels and sprocket chains may be effected, and means for driving the endless carrier.

11. A display device comprising a casing having a vision opening, an endless carrier mounted therein, display panels mounted on the endless carrier, two-part spring clips for resiliently connecting the panels to the endless carrier, crenelated reflector plates mounted rearwardly of the vision opening in the casing illuminating means between the reflector and display panels for projecting light through the display panels and vision opening and means for driving the endless carrier.

12. A display device including a casing, an endless carrier mounted therein comprising sprocket chains passing over sprocket wheels at each side of the casing, pintle bars, connecting the sprocket chains, means for detachably securing the pintle bars in place, a metallic panel frame, having hinge leaves mounted on the pintle bars, a transparent panel loosely mounted in the panel frame, and resilient means interposed between the pintle bars connecting the sprocket chains to the panel frames.

13. A display device including a casing having a display window, an endless carrier mounted within the casing comprising spaced parallel sprocket chains, detachable rods connecting the sprocket chains at spaced intervals, display panel frames hinged to the detachable rods, transparent display panels loosely carried by the panel frames, spring means for connecting the longitudinal edges of the display panel frames to the sprocket chains, and means for illuminating the display panels as they move in back of a vision opening formed in the display casing.

14. A display device comprising a casing having a window, an endless carrier mounted in the casing, display panel frames resiliently secured to the endless carrier, adapted to move in back of the casing window, an opaque plate mounted in back of the display panels adjacent the casing window, electric lamps for projecting light through the opaque plate and display panels, and a reflector positioned behind the electric lamps having angular arranged faces projecting between adjacent lamps.

15. In display apparatus of the character described, a carrier and a panel frame supported by the carrier, the support including a tensioned clip formed of relatively movable parts resiliently engaged with the carrier and loosely engaged with the panel frame.

16. In display apparatus of the character described, a carrier and a panel frame supported by the carrier, the support including a tensioned clip formed of relatively movable parts resiliently engaged with the carrier and loosely engaged with the panel frame, and said clip being constructed and arranged to permit substantially universal movements between the carrier and panel frame whereby all strains are removed from the panel frame.

GEORGE F. REED.
